DESIGN FOR A FITTED POCKETBOOK

Florence N. Lewis, New York, N. Y.

Application August 29, 1934, Serial No. 53,109

Term of patent 3½ years

To all whom it may concern:

Be it known that I, FLORENCE N. LEWIS, a citizen of the United States, residing at New York, in the county of New York, and State of New York, have invented a new, original, and ornamental Design for Fitted Pocketbooks, of which the following is a specification, reference being had to the accompanying drawing, forming part thereof.

Figure 1 is a perspective view of a fitted pocketbook in closed position.

Figure 2 is a perspective view of the fitted pocketbook in open position showing the ornamental appearance of its interior on one side of the central partition, and

Figure 3 is a similar view showing the ornamental appearance of the compartment on the opposite side of the central partition.

I claim:

The ornamental design for a fitted pocketbook, as shown.

FLORENCE N. LEWIS.
